US00D912356S

(12) **United States Design Patent** (10) **Patent No.:** **US D912,356 S**
(45) **Date of Patent:** **** Mar. 2, 2021**

(54) **CLEAT CLEANING TOOL**

(71) Applicants: **Luke R Schneider**, Altamonte Springs, FL (US); **Peter W Hosbein**, Altamonte Springs, FL (US)

(72) Inventors: **Luke R Schneider**, Altamonte Springs, FL (US); **Peter W Hosbein**, Altamonte Springs, FL (US)

(**) Term: **15 Years**

(21) Appl. No.: **29/697,269**

(22) Filed: **Jul. 6, 2019**

(51) LOC (13) Cl. **07-05**

(52) U.S. Cl.

USPC **D32/47; D21/793**

(57) **CLAIM**

We claim the ornamental design for a cleat cleaning tool, as shown and described.

DESCRIPTION

A portion of the disclosure of this patent document contains material that is subject to copyright protection. The copyright owner has no objection to the facsimile reproduction by anyone of the patent document or patent disclosure as it appears in the Patent and Trademark office, patent file or records, but otherwise reserves all copyright rights whatsoever.

FIG. 1 is a top front right perspective view of the invention. FIG. 2 is a bottom rear left perspective view of the invention.

FIG. 3 is a top plan view of the invention.

FIG. 4 is a right side view of the invention.

FIG. 5 is a bottom plan view of the invention.

FIG. 6 is a rear plan view of the invention.

FIG. 7 is a front plan view of the invention.

FIG. 8 is a left side view of the invention.

FIG. 9 is a top front right perspective view of a second embodiment of the invention.

FIG. 10 is a bottom rear left perspective view of a second embodiment of the invention.

FIG. 11 is a top plan view of a second embodiment of the invention.

FIG. 12 is a right side view of a second embodiment of the invention.

FIG. 13 is a bottom plan view of a second embodiment of the invention.

FIG. 14 is a rear plan view of a second embodiment of the invention.

FIG. 15 is a front plan view of a second embodiment of the invention; and,

FIG. 16 is a left side view of a second embodiment of the invention.

The middle portions of the cleat cleaning tool shown in broken lines indicate indeterminate length and forms no part of the claimed design.

1 Claim, 6 Drawing Sheets
